UNITED STATES PATENT OFFICE.

ARTHUR RONALD TRIST, OF ST. ALBANS, ENGLAND.

PACKING FOR STUFFING-BOXES OR SIMILAR DEVICES.

No. 885,405.

Specification of Letters Patent.

Patented April 21, 1908.

Application filed December 11, 1907. Serial No. 406,033.

To all whom it may concern:

Be it known that I, ARTHUR RONALD TRIST, a subject of the King of Great Britain and Ireland, residing at St. Albans, Hertfordshire, England, have invented new and useful Improvements in and Relating to Packing for Stuffing-Boxes and Similar Devices, of which the following is a specification.

This invention relates to packing for stuff-
10 ing boxes and the like and has particular reference to the form of packing which is of **U**-section having a thick heel on one side and a tapering flexible tongue or lip on the other side.

15 This invention has for its object the construction of such packing in such a way as to prevent the gland pressure on the packing from deforming the heel portion thereof and preventing the spreading of such heel, in
20 order to avoid lateral pressure of the heel upon the tongue of the packing.

25 A further object of my invention is to transmit the pressure of the gland on the heel directly to that portion of the packing where the bend is situated and thus preserve the space between the heel and the tongue so that the fluid pressure can force the tongue against the rod or other device against which the packing forms a sliding joint.

30 To carry the invention into effect, I construct the heel of the packing on that side adjacent to the tongue of harder material than the remainder of the packing. This may be done by varying the composition of
35 the rubber constituents of which the packing is made so that upon vulcanization the inner portion of the heel is harder in character than the rest. Or, I may form this portion of metal such as Babbitt metal or other
40 equivalent material, or I may incorporate with the ordinary cloth or other material and india-rubber or the like, metal wire gauze. This hardened or stiffened portion preferably stretches from the extreme heel to
45 the curved portion where the tongue is

turned round upon the heel so that the pressure of the gland or of the adjacent rings upon this hardened portion is transmitted direct to the curved portion without any tendency of producing deformation. 50

In order that the invention may be the better understood I will now proceed to describe the same in relation to the accompanying drawing reference being had to the letters and figures marked thereon. 55

The drawing shows in section a gland with my improved packing placed therein.

The packing consists of layers of cloth *a* held together by a body of india-rubber *b* and having a tapering flexible lip or tongue *c* 60 adapted to bear against the surface of the rod *d*. On the inner portion of the packing I arrange a hardened or stiffened portion *e* formed for example of wire gauze embedded in an india-rubber matrix and of such a form 65 as to transmit pressure from the gland *f* through each layer of the packing to the next layer of packing and in such a manner as to prevent the heel *g* from being deformed by such pressure filling up the space *h* and 70 pressing against the lip or tongue *c*.

I claim:—

1. In a packing of **U**-section having a thick heel on one side and a tapering flexible lip or tongue on the other side, the provision of a 75 hardened or stiffened portion in the said heel through which the gland pressure is transmitted through the various layers of packing so as to prevent the deformation of the heel by such pressure, substantially as described. 80

2. A packing of **U**-section having a thick heel on one side and a tapering flexible lip on the other side.

In testimony whereof I have signed my name to this specification in the presence of 85 two subscribing witnesses.

ARTHUR RONALD TRIST.
